UNITED STATES PATENT OFFICE.

MAX SCHWERTFÜHRER, OF STUTTGART, GERMANY.

LOCKING DEVICE FOR PRINTING-PLATES.

SPECIFICATION forming part of Letters Patent No. 436,614, dated September 16, 1890.

Application filed May 14, 1890. Serial No. 351,799. (No model.)

To all whom it may concern:

Be it known that I, MAX SCHWERTFÜHRER, a citizen of Germany, residing at Stuttgart, Kingdom of Württemburg, Germany, have invented a new and useful Improvement in Locking Devices for Printing-Plates, of which the following is a specification.

My present invention is intended as a substitute for the adjustable clamps heretofore used in printing establishments and which held the plates in place by means of screws. Said invention relates to an arrangement wherein a single light blow upon a headed pin provided for the purpose suffices to draw the clamp down upon the printing-plate and the latter upon the bed. The loosening of the clamp is effected with equal ease by means of a hooked key.

In the drawings accompanying this specification, Figure 1 represents a vertical transverse section, Fig. 2 a vertical longitudinal section, Fig. 3 an end view, and Fig. 4 a plan, of a locking device or adjustable clamp embodying my invention; and Figs. 5 and 6 a side elevation and plan, respectively, of a printing surface and bed, showing the said clamp in position.

The clamp *f* is attached to a box or shell *H*, whose bottom is inclined with relation to its top. The box or shell *H* has no lateral walls. Within said shell *H* there is a wedge *K*, adapted to slide on its bottom, and which is slightly broader than said bottom, and which, with its faces *k'*, bears laterally against the inclined surfaces of the dovetail grooves *a* of the bed *F* whenever the wedge *K* is urged forward upon the bottom of the shell *H*. This forward movement is effected by pressure or a blow upon the head of the pin *S*, formed integral with the wedge *K* and projecting through the front wall of the shell.

The operation is as follows: When the wedge *K* is urged forward upon the inclined bottom of shell *H* in the direction indicated by the arrow, its two lateral faces *k'* are brought into contact with the inclined surfaces of the dovetail groove *a* of the bed. A further advance of the wedge results in a pressure upon the inclined bottom of shell *H*, which is thus carried downward, drawing the clamp *f* down upon the beveled edge of the printing-plate *D* (see Fig. 6) and the latter upon the bed *F*.

The shell *H*, together with its wedge *K* and the pin *S*, lies wholly within the groove *a* and

below the upper surface of the bed *F*, the clamp *f* alone projecting beyond the same.

The loosening of the locking device is effected by means of a hook-shaped key, which grasps the head of the pin *S* to withdraw the wedge *K*.

It will be noticed that inasmuch as the clamp *f* extends obliquely to the length of the shell and the wedge *K* the strain upon said clamp and consequently upon the wedge will not be in the direction of its length, and hence such strain will not act to loosen the plate-lock. The plate will thus be securely held upon the bed *F*.

What I claim, and desire to secure by Letters Patent, is—

1. In a locking device for printing-plates, the combination, with a shell provided with a plate-clamp, of a wedge adapted to slide within said shell, and means for drawing the shell downward upon the forward movement of the wedge, all substantially as described.

2. In a locking device for printing-plates, the combination of a shell having an inclined bottom and provided with a clamp extending obliquely to its length and a wedge adapted to slide within said shell, substantially as and for the purposes set forth.

3. In a locking device for printing-plates, the combination, with a shell provided with a clamp and having an inclined bottom, of a wedge having lateral wedge-faces and adapted to slide within said shell, and a bed having dovetail grooves, substantially as described, whereby the wedge will be caused to bind against the faces of its dovetail grooves when urged forward, all substantially as described.

4. A locking device for printing-plates, consisting of a shell *H*, arranged in the grooves of the bed, open at its sides, and having an inclined bottom, and a wedge adapted to slide on the inclined bottom provided with a pin *S*, whose inclined sides *k* bear against the inclined sides of the dovetail grooves *a* of the bed *F* when the said wedge is urged forward, and thereby secure the printing-plate on the bed *F* by the depression of the shell *H* and its clamp.

In testimony whereof I have signed this specification in the presence of two subscribing witnesses.

MAX SCHWERTFÜHRER.
